UNITED STATES PATENT OFFICE

124,111

DESIGN FOR A DRESS ENSEMBLE

Julia Richards, Brooklyn, N. Y.

Application October 28, 1940, Serial No. 96,123

Term of patent 3½ years

To all whom it may concern:

Be it known that I, Julia Richards, a citizen of the United States, residing at 1346 63rd St., Brooklyn, in the county of Kings and State of New York, have invented a new, original, and ornamental Design for a Dress Ensemble, of which the following is a specification, reference being had to the accompanying drawing, forming part thereof.

I claim:

The ornamental design for a dress ensemble, substantially as shown.

JULIA RICHARDS,
